UNITED STATES PATENT OFFICE

JOSEPH BUTZEN, OF CICERO, ILLINOIS

APPLIANCE FOR BOOTS AND SHOES

Application filed September 10, 1927. Serial No. 218,741.

This invention pertains to the general class of devices for the purpose of relieving the shocks to the system incident to walking and particularly to appliances for boots and shoes 5 to prevent and diminish such shocks.

An object of applicant's invention is the production of a device to be incorporated in boots and shoes for the purpose of relieving shocks to the feet and other parts of the 10 man body.

A further object of applicant's invention is the production of a device of this character that is durable, efficient, of low cost, of small 15 number of parts, and the serviceability of which is not decreased with use.

A further object of applicant's invention is the production of a device which may be readily inserted in boots and shoes for the purpose of relieving shocks, of long lasting qualities, 20 the resiliency of which may be adjusted by a small interchange of parts to suit the particular needs of the wearer.

A further object of applicant's invention is the production of a device for the purpose of 25 relieving shocks and to be incorporated in footwear, said device being enclosed from the weather and out of contact with the elements.

Many other objects and advantages of the construction herein shown and described will 30 be obvious to those skilled in the art from the disclosure herein given.

Applicant is aware that there are various devices on the market for the purpose of relieving shocks to the foot and particularly 35 the heel. The ordinary rubber heel is well known; however, the rubber heel has its greatest utility when new, which greatly decreases with wear and other causes until the rubber heel is worn out. In applicant's device the 40 same degree of resiliency is maintained throughout regardless of the amount of wear sustained by the heel. Furthermore, devices have been produced for similar purposes in which the resilient members are placed within 45 the heel proper, the heel having collapsible sides, unsightly in appearance and requiring in most instances a specially constructed shoe for their adaptation thereto. Applicant's device may be incorporated into any style of 50 boot or shoe, either fancy, dress or work boots

and shoes, ladies', children's or men's, without altering in any way the outside appearance of same.

To this end my invention consists in the novel construction, arrangement and combination of parts herein shown and described, and more particularly pointed out in the 55 claims.

In the drawings, wherein like reference characters indicate like or corresponding 60 parts:—

Fig. 1 is a sectional elevation through the heel portion of a shoe showing the novel appliance incorporated therein, part of the shoe being shown in dotted lines; 65

Fig. 2 is a bottom plan view of the device;

Fig. 3 is a section on line 3—3 of Fig. 1;

Fig. 4 is a sectional view of a modification; and

Fig. 5 is a sectional view of a modification. 70

Referring now to Fig. 1, 1 shows a conventional shoe shown partly in dotted lines, 2 is the outer sole thereof, 3 the usual inner sole, 4 the heel and 5 the upper, the latter being shown in dotted lines. At 6 a circular depression is preferably formed in the floor of the shoe at the rear thereof from the inside downward through the inner and outer sole and into the heel proper. In the preferred embodiment this depression is cylindrical in shape. 75

Applicant's appliance comprises a base portion 7 shaped similar to the innersole 3 at the heel and extends forward preferably to the arch, resting upon the innersole 3. Base 7 is formed of suitable material, preferably 80 pliable such as leather, rubber or other suitable substance, but may be shaped from more rigid material such as wood or metal. The base portion is preferably covered with a covering 8 on its upper surface which may be of canvas, chamois, leather or other material used in shoe construction. The base portion 7 has formed on the under side thereof a raised portion 9, either integral or attached thereto by suitable means, which is preferably 85 circular and is formed with a groove 10 around its outer circumferential surface for the purpose of accommodating and holding the upper end of spring 11. The spring 11 at its bottom end rests on the bottom of the de- 90

100

pression 6. The spring 11 is of such length that it protrudes above the upper edge of the depression 6 a slight amount, the purpose of which will be readily seen. The spring 11 5 protruding above the depression 6 holds the bottom surface 12 of the base 7 a short distance above the upper face 13 of the inner sole 3. This is to allow for a slight relative motion between the base 7 and the inner sole 3.

10 In adapting applicant's device to the ordinary shoe, it is merely necessary to form the depression 6 in the heel portion thereof a proper depth, inserting the appliance and the shoe is ready to be worn. Shoes, however, 15 may be constructed with the depression already formed in the heel portion thereof. For shoes with narrow heels, such as ladies' shoes for instance, the depression 6 is of relatively smaller diameter and the size of the 20 spring 11 selected to suit the wearer. In shoes with wider heels such as men's shoes, the depression 6 is of relatively larger diameter and the size of spring 11 is selected accordingly. The term "size" above referred 25 to is used in the sense of the amount of force required to compress the spring a desired distance. For instance, a larger size would require a greater amount of force.

It is not intended that the entire weight 30 thrust upon the heel shall be borne by the spring 11. The spring 11 is merely intended for the purpose of relieving the shock, the downward movement of base 7 being brought to rest by the under surface 12 thereof coming in contact with the surface 13 of the inner sole 3. The proper size of spring 11 will 35 be left somewhat to the choice of the wearer of the shoe. However, should the wearer of the shoe desire to have the heel of the foot entirely supported by the spring, it is only necessary to insert a larger size (or stronger) 40 spring, or the spring already in use may be stretched if of relatively large size.

It is obvious that applicant's appliance may 45 be worn with shoes either with or without rubber heels. There is no necessity for a rubber heel; however, should the wearer choose to have same applied, same will not interfere in any way with the operation of 50 applicant's device. This device is of particular utility in large work shoes and boots, particularly hob-nail boots and shoes and those having steel plates applied to the under surface thereof.

55 In Fig. 4 is shown a modification preferable when rubber heels are attached. A plate 14 of metal or other suitable material is placed between the upper portion of the heel 4' and the attached rubber heel 15. 60 Spring 11' rests on plate 14. 4', 14 and 15 are secured together by any suitable means, which may be by the usual nails used to attach rubber heels.

In Fig. 5 plate 14' is inserted in a recess 65 16 formed in the heel 4''. In the latter form

the plate is not exposed to view or the elements, and is often preferable.

Furthermore, the relative movement between the innersole 3 and the base 7 need not be very great to obtain the desired degree of resiliency. In fact the spring need not be compressed any more than the ordinary rubber heel is compressed to obtain the same degree of shock absorbing qualities.

70 It is readily seen that after the pair of shoes is worn out, the device may be removed therefrom and placed in the next pair of shoes. To restore lost resiliency it is only necessary to slightly stretch the spring.

Having thus described my invention, it is 75 obvious that various immaterial modifications may be made in the same without departing from the spirit of my invention; hence I do not wish to be understood as limiting myself to the exact form, construction, 80 arrangement and combination of parts herein shown and described, or uses mentioned.

85 What I claim as new and desire to secure by Letters Patent is:

1. In combination, a shoe, a depression in 90 the inner bottom portion thereof at the heel, a resilient member in said depression and forming frictional contact with the sides of the latter, and a base portion above the depression independent of the innersole of the 95 shoe, said base portion clamped and supported by said resilient member.

2. In combination, a shoe, a depression in 100 the floor thereof at the rear, said depression extending through the floor of the shoe into the heel of the shoe, a resilient member within and guided by said depression, a base portion above the depression adapted to contact the heel of the foot, said base portion clamped and resiliently supported by said resilient member, said base portion resting upon the innersole when the downward force thereon 105 is greater than the upward force of the resilient member.

110 In testimony whereof, I have hereunto signed my name.

JOSEPH BUTZEN.
